UNITED STATES PATENT OFFICE

HENRIE L. SCOTT, OF SAN ANTONIO, TEXAS

INCLINED FLOOR GARAGE

Application filed November 3, 1930. Serial No. 492,989.

The present invention pertains to a novel building of a type particularly adapted for parking automobiles and like vehicles.

The primary object of the present invention is to devise a garage or automobile parker which is particularly adapted for receiving the automobiles of employees in large factories, patrons of ball parks or theatres or any place where practically all the 10 people will want their automobiles at or about the same time. In such a garage the primary consideration is that of location, for it is apparent that to serve efficiently and meet the demands of the public that it must 15 be conveniently located. The presence of a factory, ball park, theatre, etc., increases the value of the property surrounding it and therefore to put a parking proposition on a paying basis it must utilize every inch of 20 space to the fullest advantage, and a building embodying the primary invention, constructed approximately one hundred feet by one hundred and twenty-eight feet and extending approximately one hundred feet 25 above the ground level will park approximately two thousand seven hundred automobiles, these figures serving to illustrate the advantages of the present invention over conventional parkers.

30 The present invention comprises a building having inclined floors and elevators at each end thereof having inclined platforms for receiving the automobiles. The elevators at one end of the building carries a plurality of automobiles to the proper floor levels and discharges them so that they run by force of gravity through the building to the elevator at the opposite end of the building which again conveys the automobile to 35 the ground level. Automatic mechanisms are provided for discharging the automobile from the elevator platforms to the inclined floors, from the inclined floors to the elevator platforms at the discharging end of 40 the building, and from the latter elevators to the ground level again, it being a feature of the present invention that it is not necessary that attendants handle the automobile during the entire operation.

45 With the above and other ends in view,

the invention consists in matters herein-after set forth and more particularly pointed out in the appended claims, reference being had to the accompanying drawings, in which—

55

Figure 1 is a vertical cross sectional view of a building constructed in accordance with the present invention;

Fig. 2 is a fragmentary cross sectional view illustrating the releasing means which 60 permits an automobile to be discharged from the floor to the elevator platform;

Fig. 3 is a cross sectional view taken on the line 3—3 of Figure 2;

Fig. 4 is a view corresponding to Figure 65 3, illustrative of a further stage of operation;

Fig. 5 is a cross sectional view taken substantially on the line 5—5 of Figure 3;

Fig. 6 is a fragmentary view illustrative 70 of the mechanism which releases the releasing means illustrated in Figure 3;

Fig. 7 is a view of the releasing mechanism on the elevator which discharges the automobile to the ground level, taken on the 75 line 7—7 of Figure 8;

Fig. 8 is a cross sectional view through the elevator platform, illustrating the releasing means contained therein;

Fig. 9 is a cross sectional view, taken on 80 the line 9—9 of Figure 8;

Fig. 10 is a cross sectional view of one of the elevators which receive the automobiles to carry them to the floors, illustrating the automatic means for releasing the automobile to permit it to roll onto the inclined floor; and

Fig. 11 illustrates the means for actuating the releasing means illustrated in Figure 10.

90

Like characters of reference are employed throughout to designate corresponding parts.

The numeral 1 indicates a building which extends approximately an equal distance 95 above and below the ground surface, and constructed within this building in a manner known to the trade, are inclined floors 2. At each end of the floors are elevator shafts 3 and 4, the shafts being arranged in pairs 100

so that the elevator cables may be trained over pulleys or sheaves at the top of the shafts so that two elevators may be operated by a single motor and so that one elevator counterbalances another elevator.

Adjacent the elevator shafts 3 is formed an entrance 5 having an inclined ramp or ground surface 6 so that an automobile will roll through the entrance when the brakes thereon are released. A tunnel 7 is provided to permit persons leaving their automobiles adjacent the entrance to pass to the street without the necessity of crossing that portion of the ground surface which would interfere with incoming automobiles.

In the elevator shafts 3 are mounted elevators 8 having cables 9 secured thereto and trained over pulleys or sheaves 10 and a power cable 11 secured thereto and trained over a motor driven pulley 12, each cable having its two ends secured to two elevators so that when one goes up the other goes down and one elevator counterbalances the other. Each elevator has a plurality of inclined platforms 13 and when one of these platforms is in line with the ground surface 6 an automobile is permitted to roll onto the elevator until its front axle comes in contact with the arm 14 which projects up through each of the several platforms. As a result of the fact that one elevator goes up when the other goes down it is possible to successively load an automobile on the platforms of two elevators at the same time.

When all the platforms of the elevator have been loaded with automobiles (with the exception of the lowermost platform which is supported by flexible members in a manner and for a purpose to be described later) it is desired to move the arms 14 so that they permit the automobiles to roll by force of gravity off the inclined platforms. This is accomplished by making the arm 14 part of a lever 15 which is pivoted to the bottom of the elevator platform so that a portion thereof projects out beyond the side of the elevator. A spring 16 resiliently holds the arm 14 projecting up through the slot 17 in the platform. An elongated strap member 18 is slidably supported on the side of the elevator and each of the levers 15 are connected thereto as indicated by the numeral 19 (see Fig. 10) so that when the strap member is moved vertically the lever 15 is pivoted and thereby lowers the arm 14 to permit the automobile to pass over the same. To operate the strap member 18 a lever 20 is pivoted on the side of the elevator and one end of the lever is connected to the top of the strap member while the opposite end is bent outwardly as at 21 so that it comes in contact with an obstruction 22 formed at the top of the elevator shaft, so that when the elevator comes to the top of its travel it pivots the lever 20

and raises the strap member 18 so that each arm 14 is lowered. When the elevator comes to the lowermost point of its travel the end of the strap member 18 comes in contact with an obstruction or with the bottom of the elevator shaft so that the strap member is raised and thereby lowers the arms 14.

When the automobiles leave the platforms 13 they roll down the inclined floors 2 until the front axle of respective automobiles contact with respective arms 23 located adjacent the elevator shafts 4. The next automobile is held by the first automobile when its front bumper contacts with the rear bumper thereof, and to insure alignment which will prevent damage to the automobiles there are provided guide members on the inclined floors in the shape of channels 24 spaced apart a distance corresponding to the spacing of the automobile wheels.

Elevators 25, mounted and constructed similar to the above described elevators 8, are mounted in the shafts 4 and are provided with inclined platforms 26, and these elevators just prior to the limit of their upward or downward movement come in contact with levers 27 and cause the same to be raised or lowered respectively and thereby raise or lower the strap members 28 which are slidably mounted at the sides of the floors. A strap member 28 is provided for the set of floors above the ground level and one is provided adjacent each elevator for the set of floors below the ground level and Figure 6 illustrates a fragment of the elevator with a projecting member 29 formed thereon to contact with the lever 27 and raise the strap member 28, the lever 27 being hinged as at 30 so that it may bend when the projecting member 29 passes in the opposite direction, suitable spring means being employed to hold the lever extended.

When the projection 29 contacts with the lever 27, the end of the latter is raised and the strap member is jerked upwardly until the projection raises to such a point that the end of the lever slips past the same and the strap member is again free to resume its normal position. Toggle members 31 are received in recesses 32 as illustrated in Figure 3, and when the strap member moves upwardly the members 31 force it outwardly to the position illustrated in Figure 4. A spring member 33 normally holds the strap member in its inward position which also causes the lever 27 to resume its normal position.

The arms 23 which holds the automobiles from rolling onto the elevators 25 are formed on wheels 34 and six of such arms are illustrated, but it is understood that the invention is not confined to this number, they merely being shown by way of example.

Three holes 35 are formed in the wheel and a pin 36 which is connected to the strap member 28 is adapted to enter one of said holes in a manner to prevent rotation of said 5 wheel and thereby prevent movement of the automobiles. When the elevator is just about to the position the strap member is jerked upwardly and outwardly in the manner above described, and in so doing the pin is 10 jerked out of the hole 35 and the weight of the automobile as it rolls down the incline rotates the wheel 34 so that when the strap member is again ready to resume its inward position the hole is out of line with the pin 15 36 and the latter brushes the side of the wheel until the next hole comes in line. The next hole 35 is forced in line with the pin 36 by the front axle of the succeeding automobile coming in contact with the next arm 20 23 and the next automobile is held until the elevator goes down and is unloaded and comes up again, the operation being the same on the floors located below the ground level.

When the automobiles roll onto the elevator platform 26 they are prevented from 25 rolling off the opposite side thereof by upwardly projecting arms 37. Each arm is bent substantially at right angles to form a portion 38 which is received in the guide 39, 30 the end of the portion 38 resting upon a shoulder formed on a lever 40 as indicated at 41, the lever 40 being received in a bracket 42 which permits pivotal movement of the lever. The arm 26 is held projecting 35 upwardly through a slot 43 in the platform 26 by means of a spring 44 which is secured to the bottom of the platform 26. These platforms are to discharge the automobiles only at the exit 45 which is also inclined as 40 at 46 and provided with a tunnel 47 to permit persons to come to the exit to get their automobiles without crossing the path of automobiles leaving the building.

Adjacent the exit is formed a projection 45 48 against which the levers 40 strike when the platforms come in line with the exit while either moving up or down. When the elevator is moving upwardly the lever 40 is tilted in the bracket 42 so that the opposite 50 end moves upwardly. The shoulder contacting with the portion 38 of the arm at 41 causes the latter to rock in the guide member 39 and thereby lower the arm 26. When the elevator is moving downwardly the lever 40 is 55 rocked so that the end thereof is lowered and a finger 49 which hooks over the arm 26 pulls the latter downwardly.

At the bottom of each elevator is mounted an inclined platform 50, being supported by 60 suitable flexible members 51 such as chains. These platforms have no means for stopping the movement of the automobiles thereon for their purpose is for loading or unloading the floor which is in line with the ground 65 surface. They are supported by flexible

members in order that they may be collapsed as illustrated in Figure 1, in order that the lowermost rigid platforms may come in line with the lowermost floor levels.

Means for preventing the automobiles 70 from entering the entrance 5 or leaving the exit may be provided and constructed similar to any of the above described stops and abutments, or steps may be provided adjacent the exit and in this manner a garage or 75 automobile parker which is entirely automatic may be constructed for it is apparent from the foregoing that it is unnecessary that attendants should do anything more than place the automobiles in line with the 80 entrance 5 and release their brakes so they may coast down the inclines.

Although a specific embodiment of the 85 present invention has been illustrated and described it is to be understood that various structural changes may be made within the scope of the appended claims without departing from the spirit of the invention, and such changes are contemplated.

What I claim is:—

1. An automobile parker comprising a plurality of inclined floors disposed with approximately an equal number above and below the ground surface, elevators having a plurality of platforms for conveying automobiles to one end of all of said inclined floors and for discharging them onto all of said floors simultaneously so that they run by force of gravity to the opposite ends of said floors, and elevators having a plurality 95 of platforms for receiving one automobile from all of said floors simultaneously and for conveying them to the ground surface.

2. An automobile parker comprising inclined floors, elevators having a plurality of platforms for receiving and conveying automobiles to the higher end of all of said floors, automatic means for discharging all of said automobiles simultaneously from said platforms onto said floors whereby they roll by 105 force of gravity to the lower end of said floors, and elevators for receiving an automobile from the lowermost ends of said floors.

3. An automobile parker comprising a 115 plurality of inclined floors disposed with approximately an equal number above and below the ground surface, elevators having a plurality of platforms for conveying automobiles to the higher end of said floors, automatic means for discharging said automobiles onto all of said floors simultaneously whereby they roll by force of gravity to the lower end of said floors, and elevators for receiving an automobile from the lowermost 120 ends of each of said floors simultaneously.

4. An automobile parker comprising inclined floors, elevators for conveying automobiles to each of said floors simultaneously, said elevators having a plurality of inclined 125

platforms for receiving said automobiles, automatically releasable means for holding said automobiles on said platforms, elevators adjacent the lower end of said floors and 5 having a plurality of platforms for receiving an automobile from each of said inclined floors simultaneously, and automatically releasable means on each of said floors adjacent and operated by said last named eleva- 10 tors.

5. An automobile parker comprising a plurality of inclined floors disposed with approximately an equal number above and below the ground surface, elevators oper- 15 able in pairs for conveying automobiles to all of said floors simultaneously, said elevators having a plurality of inclined platforms for receiving said automobiles, automatically releasable means for holding said auto- 20 mobiles on said platforms, elevators adjacent the lower end of said floors and operable in pairs for receiving an automobile from all of said inclined floors simultaneously, and automatically releasable means on 25 each of said floors adjacent and operated by said last named elevators.

6. An automobile parker comprising inclined floors, elevators having a plurality of platforms for conveying automobiles to all 30 of said floors, a plurality of elevators having inclined platforms mounted adjacent the lower ends of said floors, automatically releasable means for holding said automobiles on each of said floors and for discharging 35 one at a time from each floor onto all of said inclined platforms simultaneously, and automatically releasable means for holding said automobiles on said platforms and for discharging said automobiles from any plat- 40 form in line with the ground surface.

7. An automobile parker comprising a plurality of inclined floors disposed with approximately an equal number of floors above and below the ground surface, eleva- 45 tors operable in pairs for conveying auto- mobiles to all of said floors simultaneously, elevators operable in pairs and having inclined platforms mounted adjacent the lower ends of said floors, automatically releasable means for holding said automobiles on 50 said floors and for discharging one at a time from each platform onto all of said inclined platforms simultaneously, and automatically releasable means for holding said auto- 55 mobiles on said platforms and for discharging said automobiles from any platform in line with the ground surface.

8. An automobile parker comprising inclined floors, elevators having a plurality of inclined platforms for carrying automobiles to all of said floors simultaneously, automatically releasable means for holding said automobiles on said inclined platforms and for permitting said automobiles to roll off 65 all of said inclined platforms simultaneously

when said platforms are in line with the proper floors, elevators adjacent the lower ends of said inclined floors having a plurality of inclined platforms, automatically releasable means on said floors adjacent said last named elevators for holding said automobiles and for discharging one automobile onto each of the inclined platforms of said elevator simultaneously, and automatically releasable means on said inclined platforms of said last named elevators adapted to permit the automobiles to roll from the platforms in line with the ground surface. 75

9. An automobile parker comprising a plurality of inclined floors disposed with approximately an equal number above and below the ground surface, elevators operable in pairs and having inclined platforms for carrying automobiles to said floors, automatically releasable means for holding said 80 automobiles on said inclined platforms and for permitting said automobiles to roll off all of said inclined platforms simultaneously when said platforms are in line with the proper floors, elevators adjacent the lower 85 ends of said inclined floors having inclined platforms, automatically releasable means on said floors adjacent said last named elevators for holding said automobiles and for discharging simultaneously one automobile 90 onto each of the inclined platforms of said elevator, and automatically releasable means on said inclined platforms of said last named elevators adapted to permit the automobiles to roll from the platforms in line 95 with the ground surface. 100

10. An automobile parker comprising inclined floors, means for conveying automobiles to one end of each of said inclined floors and for discharging them on said floors simultaneously so that they run by force of gravity to the opposite ends of said floors, and means for receiving an automobile from each of said floors simultaneously and for conveying them to the ground 105 surface. 110

11. An automobile parker comprising a plurality of inclined floors disposed with approximately an equal number above and below the ground surface, means for conveying 111 automobiles to one end of each of said inclined floors and for simultaneously discharging them on said floors so that they run by force of gravity to the opposite ends of said floors, and means for simultaneously receiving an automobile from each of said floors and for conveying them to the ground 116 surface. 12

12. An automobile parker comprising elevators arranged in pairs and suspended in a manner whereby one elevator counterbalances another and travels in an opposite direction in relation thereto, inclined platforms on said elevators adapted for receiving automobiles, means for retaining the au- 125

tomobiles on said platforms, floors adjacent said elevators and inclined downwardly therefrom, means actuated at the upper and lower extremity of movement of said elevators 5 for releasing said automobiles whereby they simultaneously roll from said platforms onto said inclined floors and roll downwardly thereon, means at the lower end for retaining the automobiles on said floors, counterbalanced elevators having inclined platforms mounted at the lower ends of said floors, and means on said elevators for actuating said retaining means on said floors at the extremity of upward or downward movement 10 of said elevators to release an automobile from each of said floors and permit it to roll onto said platforms.

13. An automobile parker comprising elevators arranged in pairs and suspended in a 20 manner whereby one elevator counterbalances another and travels in an opposite direction in relation thereto, inclined platforms on said elevators adapted for receiving automobiles, means for retaining the automobiles on said platforms, floors adjacent said elevators and inclined downwardly therefrom, means actuated at the upper and lower extremity of movement of said elevators for releasing said automobiles whereby 25 they simultaneously roll from said platforms onto said inclined floors and roll downwardly thereon, means at the lower end for retaining the automobiles on said floors, counterbalanced elevators having inclined platforms mounted at the lower ends of said floors, means on said elevators for actuating said retaining means on said floors at the extremity of upward or downward movement 30 of said elevators to release an automobile from each of said floors and permit it to roll onto said platforms, retaining means on each of said platforms adapted to be actuated to release the automobile therefrom when a platform is opposite the ground floor, and a collapsible platform suspended on the bottom of each elevator.

35 14. An automobile parker comprising elevators arranged in pairs and suspended in a manner whereby one elevator counterbalances another and travels in an opposite direction in relation thereto, inclined platforms on said elevators adapted for receiving automobiles, means for retaining the automobiles on said platforms, floors adjacent said elevators and inclined downwardly therefrom, means actuated at the upper and lower extremity of movement of said elevators for 40 releasing said automobiles whereby they simultaneously roll from said platforms onto said inclined floors and roll downwardly thereon, means at the lower end for retaining the automobiles on said floors, counterbalanced elevators having inclined platforms mounted at the lower ends of said floors, means on said elevators for actuating said retaining means on said floors at the extremity of upward or downward movement of said elevators to release an automobile 45 from each of said floors and permit it to roll onto said platforms, and retaining means on each of said platforms adapted to be actuated to release the automobile therefrom when a platform is opposite the ground floor.

45 14. An automobile parker comprising elevators arranged in pairs and suspended in a manner whereby one elevator counterbalances another and travels in an opposite direction in relation thereto, inclined platforms on said elevators adapted for receiving automobiles, means for retaining the automobiles on said platforms, floors adjacent said elevators and inclined downwardly therefrom, means actuated at the upper and lower extremity of movement of said elevators for releasing said automobiles whereby they simultaneously roll from said platforms onto said inclined floors and roll downwardly thereon, means at the lower end for retaining the automobiles on said floors, counterbalanced elevators having inclined platforms mounted at the lower ends of said floors, means on said elevators for actuating said retaining means on said floors at the extremity 50 of upward or downward movement of said platforms.

5 elevators to release an automobile from each of said floors and permit it to roll onto said platforms, and a collapsible platform suspended on the bottom of each elevator.

15. An automobile parker comprising elevators arranged in pairs and suspended in a manner whereby one elevator counterbalances another and travels in an opposite direction in relation thereto, inclined platforms on said elevators adapted for receiving automobiles, means for retaining the automobiles on said platforms, floors adjacent said elevators and inclined downwardly therefrom, means actuated at the upper and lower extremity of movement of said elevators for releasing said automobiles whereby they simultaneously roll from said platforms onto said inclined floors and roll downwardly thereon, means at the lower end for retaining the automobiles on said floors, counterbalanced elevators having inclined platforms mounted at the lower ends of said floors, means on said elevators for actuating said retaining means on said floors at the extremity of upward or downward movement of said elevators to release an automobile from each of said floors and permit it to roll onto said platforms, retaining means on each of said platforms adapted to be actuated to release the automobile therefrom when a platform is opposite the ground floor, and a collapsible platform suspended on the bottom of each elevator.

16. An automobile parker comprising a plurality of inclined floors, elevator shafts arranged at each end of said floors and extending approximately an equal distance above and below the normal ground surface, elevators mounted in said shafts and having inclined platforms corresponding in number to the number of inclined floors and adapted to receive automobiles, means on the elevator at the higher end of said inclined floors for holding said automobiles on said platforms and adapted to be actuated at the upper extremity of movement of said elevator for releasing said automobiles whereby they roll by force of gravity onto said inclined floors and along said floors to the lower end thereof, means adjacent the opposite elevator shaft for retaining said automobiles on said inclined floors, said last named means being adapted to be actuated by the elevator in said shaft when the latter is at its upper extremity of movement for releasing said automobiles whereby they roll by force of gravity onto the inclined platforms of said elevator, and means carried on each platform for retaining the automobiles thereon and adapted to be independently actuated as each platform registers with the main floor in a manner to permit the automobiles to be discharged from said platforms.

17. An automobile parker comprising a plurality of inclined floors arranged with an equal number above and below the normal ground surface, elevators having inclined 5 platforms for receiving automobiles and adapted to register with the higher ends of all the floors above or all the floors below the ground surface at one time, means for retaining the automobiles on said platforms 10 and adapted to be automatically actuated at the upper and lower limits of movement of said elevators to release all of said automobiles whereby they roll onto said inclined floors simultaneously, similar elevators arranged adjacent the lower ends of said 15 floors, means for retaining said automobiles on said floors and adapted to be automatically actuated at the upper or lower extremity of movement of said last named elevators 20 for discharging an automobile from each floor onto the adjacent elevator platform, and means on each elevator platform adapted to be actuated independently as each platform registers with the main floor for automatically discharging the automobile from 25 each platform.

In testimony whereof I affix my signature.
